UNITED STATES PATENT OFFICE.

CLORA J. SNIDEMAN, OF WABASH, INDIANA, ASSIGNOR TO WABASH SANITRAY COMPANY, OF WABASH, INDIANA, A CORPORATION OF INDIANA.

HIGH-CHAIR TRAY.

1,361,504.

Specification of Letters Patent. Patented Dec. 7, 1920.

Application filed December 31, 1918. Serial No. 269,044.

To all whom it may concern:

Be it known that I, CLORA J. SNIDEMAN, a citizen of the United States, residing at Wabash, in the county of Wabash and State 5 of Indiana, have invented a new and useful High-Chair Tray, of which the following is a specification.

It is the object of my invention to provide a detachable sanitary tray and its 10 mounting, preferably on swinging arms, for children's high-chairs.

In some respects, the present invention is a development and improvement on the constructions shown in Patent No. 1,021,901, 15 granted April 2, 1912, to Frank H. Henley and myself, and in my prior Patent No. 1,182,938, granted May 16, 1916.

The accompanying drawings illustrate my invention: Figure 1 is a perspective view of 20 a high-chair equipped with a detachable tray mounted in accordance with my invention; Fig. 2 is a bottom view of a tray and its mounting; and Fig. 3 is an enlarged section on the line 3—3 of Fig. 2, with the tray 25 in normal position.

The high-chair is of any suitable construction, with the usual seat 10, fixed side arms 11, and back 12. Pivotaly mounted on pivot pins 13 on the two uprights 14 of 30 the back 12 are two swinging arms 15, preferably curved so as to permit their pivot points to be high. These swinging arms 15 may rest on the upper surfaces of the fixed side arms 11, or may be swung upward 35 therefrom in the usual way about the pivot pins 13.

The free ends of the swinging arms 15 are cross-connected by a U-shaped metal bar 16, the sides of which through the greater part 40 of their length bear against the under faces of the arms 15. At one point near its end, however, each side arm of the U-shaped member 16 is offset away from the under face of the corresponding swinging arm 15, 45 so as to provide a pocket between it and the arm 15 for a sliding bolt 17 movable transversely of the corresponding arm 15. Each bolt 17 is turned down at its outer end to provide a thumb piece 18 for operating it, 50 and is provided with a longitudinal slot 19 throughout the greater part of its length for permitting the passage through it of a pair of screws 20 which fasten the associated arm of the U-shaped member 16 to the 55 corresponding swinging arm 15 and also

serve as guides for the bolt 17. At about its middle, the cross-connecting member 16 is provided with a slot 21, for receiving one end of a strap 22, the other end of which may be fastened to the under side of the seat 60 10 at the front so that such strap may be passed between the knees of the occupant of the chair to hold him in it.

The tray 23 is preferably made as a stamping from a single sheet of metal, without 65 open joints; and is preferably enameled on the upper side and may be painted on the under side. This provides a thoroughly sanitary construction, by reason of the thorough cleansing which is easily obtainable. 70 The tray usually has a depressed center portion and raised edge portions. The depressed center portion fits down between the two arms 15, while the two raised portions at the ends of the tray overlap and rest upon 75 such arms. Fastened to the under side of the tray, preferably at the ends of the depressed portion, are two straps 24. The two ends of each strap 24 are offset so as to provide forwardly and rearwardly projecting 80 fingers between which and the tray bottom are open-ended pockets. The two open-ended pockets at the rear of the two straps 24 receive the base of the cross-connecting strap 16; while those at the front ends of 85 such straps receive the projecting ends of the bolts 17, as is clear from Fig. 2. When the tray is attached as shown in the drawings, it may be detached by sliding back the two bolts 17, and then sliding the tray forward to disengage it from the cross connector 90 16. The tray may be attached by the reverse operation. When attached, the tray is held in place by the interlocking action of the cross-connector 16 and the bolts 17 95 on the straps 24.

I claim as my invention:

1. A detachable sanitary tray mounting for high-chairs, comprising two swinging side arms of a chair, a cross-connector joining said two swinging side arms and swingable therewith, a detachable tray provided on its under surface with forwardly and rearwardly projecting fingers, one set of said fingers being detachably interlockable 100 with the cross-connector by forward or rearward movement of the tray, and locking members carried by said arms and movable into and out of engagement with the other fingers. 105

110

2. A detachable sanitary tray mounting for high-chairs, comprising two side arms of a chair, a cross-connector joining said two side arms, a detachable tray provided on its under surface with forwardly and rearwardly projecting fingers, one set of said fingers being detachably interlockable with the cross-connector by forward or rearward movement of the tray, and locking members carried by said arms and movable into and out of engagement with the other fingers.

3. A detachable sanitary tray mounting for high-chairs, comprising two side arms of a chair, a detachable tray, overlapping parts carried by said tray and said side arms for providing between them an interlocking connection which is releasable by relative movement between said tray and said side arms, and locking mechanism separated from said overlapping parts and mounted on and movable relatively to one of the interlocked parts, said overlapping parts and said locking mechanism acting between said tray and said side arms at more than two points.

4. A detachable sanitary tray mounting for high-chairs, comprising two side arms of a chair, a cross-connector joining said two side arms, a detachable tray, and an interlocking connection between said tray and said cross-connector, said connection being releasable and attachable by relative movement between the tray and the cross-connector, and a pair of bolts movable transversely to such tray movement for interlocking said tray and arms.

5. A detachable sanitary tray mounting for high-chairs, comprising two swinging side arms of a chair interconnected to move as a unit, a detachable tray, overlapping parts carried by said tray and said side arms for providing between them an interlocking connection which is releasable by relative movement between the tray and arms, and slide bolts spaced from said overlapping parts and acting between said tray and side

arms to interlock them and prevent such relative movement.

6. A detachable sanitary tray mounting for high-chairs, comprising two swinging side arms of a chair, a U-shaped cross-connector joining said two swinging side arms and swingable therewith, a pair of bolts mounted between said side arms and the arms of said U-shaped connector and slideable transversely of said arms, a detachable tray, a pair of straps attached to the under side of said tray and each having one end offset to form an open ended pocket to coöperate with the U-shaped connector and the other offset to provide a pocket to receive one of said bolts.

7. A detachable sanitary tray mounting for high-chairs, comprising two side arms of a chair, a U-shaped cross-connector joining said two side arms, a pair of bolts mounted between said side arms and the arms of said U-shaped connector and slideable transversely of said arms, a detachable tray, a pair of straps attached to the under side of said tray and each having one end offset to form an open ended pocket to coöperate with the U-shaped connector and the other offset to provide a pocket to receive one of said bolts.

8. A detachable sanitary tray mounting for high-chairs, comprising two side arms of a chair, a cross-connector joining said two side arms, a tray, and an interlocking connection between said tray and said cross-connector, said connection being releasable and attachable by relative movement between the tray and the cross-connector, and a releasable locking device separate from said interlocking connection and interlocking said tray and side arm.

In witness whereof I have hereunto set my hand at Wabash, Indiana, this 26th day of December, A. D. one thousand nine hundred and eighteen.

CLORA J. SNIDEMAN.
